POCKET CASE

Filed Jan. 28, 1929

Inventor:
Charles W. Morden
by *J. J. Geisler* AIA

UNITED STATES PATENT OFFICE

CHARLES W. MORDEN, OF PORTLAND, OREGON

POCKET CASE

Application filed January 28, 1929. Serial No. 335,582.

The object of my invention is to provide a novel pocket utility-case comprising in its broad aspect companion upper and lower members, slideable one in the other; the lower 5 of such members constituting a receptacle which is opened at one end in one position of the upper member.

The main object of my invention is to provide a combined match-holder and ash receptacle for smokers, especially those smoking cigarettes; also to adapt the lower receptacle of the case to constitute a safety depository for cigarette stubs and burnt matches; the safety depository further constituting 15 means operating to extinguish the cigarette stub placed therein by the closing of the case, in that way to prevent the cigarette stub continuing to burn in the case.

To this end, my invention provides a case 20 comprising upper and lower members slideable one within the other, the lower of such members constituting a receptacle, as mentioned, and the bottom of the lower member forming a partition dividing the case into 25 upper and lower compartments, the partition and bottom of the lower member converging so that the upper and lower compartments have greater depth at their opposite ends, respectively. When the case is opened the 30 lower receptacle serves as an ash receiver into which also the discarded cigarette stub may be dropped.

Then when closing the case the oblique relation of said bottoms will cause the stub to 35 be rolled under the bottom of the upper member and compressed, such action simulating the rolling of the stub under the foot; and thus the cigarette stub will be extinguished. The extinguishing of the stub and the burnt 40 match thrown into the lower receptacle is further assured by the fact that in closing the case air is excluded from the lower receptacle and thus the stub and match are smoothed.

The rolling action and compression of the cigarette stub between the bottoms of the upper and lower members also serve to diminish the cross section or thickness of the stub so that the lower receptacle will accommodate 45 several stubs, notwithstanding the relative

thinness of the case as a whole. Further, the said rolling of the stub between the bottoms of the upper and lower members facilitates the emptying of the lower receptacle since the movement of the members in again opening the case functions to roll the stubs from under the upper member so that the lower receptacle may be readily emptied.

Preferably, I also form the upper member 55 into a receptacle; and further preferably provide the same with a cover, the exterior of which is provided with a longitudinal groove adapted to have a lighted cigarette, or cigar, placed therein with its lighted end projecting over the lower receptacle when the case is 60 opened.

When the upper member of my case is 65 formed to constitute a receptacle, then, as an incidental result of the described sloping bottom of this member the receptacle so provided is so increased in depth towards one 70 end that it serves to hold a book of the paper matches in common use.

A further feature of my invention resides 75 in providing means for imposing a yielding restraint on the inadvertent moving of the members apart, and consequent opening of the case, which would cause the spilling of the contents of the lower receptacle.

The convenience of my case in its described 80 use will be apparent. It incidentally eliminates the unsightly open ash tray, and the unpleasant smell frequently incidental to a burning cigarette stub.

The described use of my invention, however, is merely illustrative of its direct purpose. Other uses will suggest themselves.

Further incidental features of my invention, and the mode of its convenient construction are hereinafter fully described with reference to the accompanying drawings illustrating the same.

In the drawings:

Fig. 1 shows a perspective view of my pocket case in a closed position, and with the book 95 of paper matches removed therefrom;

Fig. 2 shows similarly my case in an open position;

Fig. 3 shows an enlarged perspective section taken on the line 3—3 of Fig. 1; 100

Fig. 4 shows a central longitudinal perspective section of a slight modification of my case in that it is provided with a cover over the match compartment, and the end 5 wall of the lower receptacle is hinged, and illustrates the pin provided in the article-securing keeper;

Fig. 5 shows a central longitudinal section of my case as illustrated in Fig. 4;

10 Fig. 6 shows in a similar section to Fig. 5, the upper receptacle of my case removed from the lower receptacle, and illustrates a book of paper matches carried thereby;

15 Fig. 7 illustrates in a perspective view one use of my case when provided with a cover;

Fig. 8 shows a fragmentary view of a book of paper matches being inserted into the match compartment of the sliding receptacle;

20 Fig. 9 shows a book of paper matches, and illustrates the notch provided in the binding for registering with the pin in the article-securing keeper of the match compartment.

Referring now particularly to Figs. 1 to 25 3, inclusive, I have shown my pocket case comprising lower and upper receptacles *a* and *b*, the receptacle *b* being slidable within the receptacle *a*.

30 The receptacle *b* is formed of two sides *b'*, an end *c* and a bottom *d*, which slopes from the lower edge of the sides upwardly from the end *c* to almost their upper edges, and is turned inwardly as at *e* and forms a space or article-securing keeper in which the bound 35 end of a book of paper matches 2, Fig. 9 may be inserted.

35 The receptacle *a* comprises two sides *a'*, an end *g* and a bottom *h*. The upper edges of the sides *a'* are turned inwardly and downwardly as at *i* to form grooves in which the sides *b'* of the receptacle *b* are guided, when the latter is inserted within the former.

40 The lower end of the bottom *d* of the receptacle *b* is turned back on the under side 45 for a portion of its length, and then bent downward as at *k*, so as to bear on the bottom *h*, and provide a yielding resistance against the said bottom *h* so as to hold the receptacle *b* in snug slidable contact with the receptacle *a*. Also to provide a movable closure means for the open end of the lower receptacle.

45 The bottom *d* of the receptacle *b* is arranged relatively to the bottom of the receptacle *a*, so as to form a dihedral angle therewith and to provide a wider space in the opposite ends of each receptacle, respectively, in the upper of which a book of paper matches 50 2, see Fig. 9, may be contained, and in the lower of which cigarette ashes or stubs may be deposited as hereinafter described.

55 The bottom *h* of the receptacle *a* is bent inwardly on itself at the open end to form a 60 projection *j* to prevent the complete with-

drawal of the receptacle *b* after it has once been inserted in the receptacle *a*.

Inwardly projecting lugs *m* are formed on the sides *b'* of the receptacle *b* under which the edges of the book of paper matches may 70 be inserted, thus also serving as part of the article-securing keeper. A pin *n* may be provided in the space formed by the inturned portion *e*, see Figs. 4 and 5 so that only a book of matches may be inserted which has 75 been previously provided with a registering notch 3 in its binding, see Fig. 9. This feature being valuable for advertising purposes, as to replenish the matches, one would have to go to the cigar store or the like, where such 80 books of matches were dispensed.

In Figs. 4 to 6, I have shown a slight modification of my pocket case, in that a cover 4 has been provided for the receptacle *b* hinged at its end as at 5 and provided with a longitudinal cigarette holding groove 6, so that when the case is opened a cigarette may be laid thereon with the lighted end projecting over the lower compartment *b*, see Fig. 7, 85 so that the falling ashes and burning particles 90 of the cigarette will drop into the lower compartment.

As shown in Figs. 4 and 5 the end *g'* of the receptacle *a* is hinged as at *p* so that access 95 may be had to the lower compartment without withdrawing the receptacle *b*.

In this modification with the provision of the cover over the match compartment and the hinged end *g'* of the receptacle *a*, the sliding feature of the receptacle *b* may be 100 eliminated and the two receptacles fastened permanently together as access to the said lower compartment is already provided by the said hinged end *g'*.

105 Finger hold notches *r* are provided on the sides *b'* of the upper receptacle *b*, see Figs. 2 and 6, which are so arranged as to be concealed by the side walls of the lower receptacle when my case is closed, and exposed when it is opened. By this means the flap of the book of matches 2 may be conveniently grasped to open it. Also, by this arrangement, as a safety measure, the book of matches cannot be readily opened until the case has been opened and the lower compartment exposed ready to receive a burnt match 110 after it is used.

115 Also, when my case has been provided with the cover 4, the said notches *r* provide a ready means for grasping the same to open it.

In the use of my pocket case when a cigarette stub designated as 7 is deposited therein and the case is closed the stub will be rolled and snuffed out by the rolling action of the bottom *d*. Furthermore, the lower chamber 120 being closed from the atmosphere will tend to smother any embers which might remain in the stub.

125 Another feature of this construction is, that when the case is opened to empty it the 130

backward movement of the bottom *d* will tend to release the old stubs so that they may be conveniently shaken out.

To replace the book of matches 2 with a fresh one it is only necessary to pull out the old book and insert the new one, as illustrated in Fig. 8, by holding the book with the cover underneath and first sliding the cover under the lugs *m* and then moving it backward until the binding is engaged under the inwardly turned portion *e*.

I claim:

1. In a pocket case, a lower receptacle consisting of a bottom having walls along its opposite sides and at one end, the opposite end of the bottom of the lower receptacle being provided with a stop, said side walls being formed to constitute guides, an upper receptacle sliding in said guides, in one position opening the case at one end, the bottom of the upper receptacle converging with that of the lower receptacle towards the opposite end of the case, the bottom of the lower receptacle provided with a resilient member on its under side bearing on the bottom of the lower receptacle, whereby said lower member functions to restrain the opening of the case, also as movable closure means for one end of the lower receptacle, said stop engaging with said member.

2. In a pocket case, a lower receptacle consisting of a bottom having walls along its opposite sides and at one end, the opposite end of the bottom of the lower receptacle being folded in to form a stop, said side walls being formed to constitute guides, an upper receptacle sliding in said guides, in one position opening the case at one end, the bottom of the upper receptacle converging with that of the lower receptacle towards the opposite end of the case, the bottom of the lower receptacle provided with an extension turned back and under and terminating in a perpendicular leg bearing on the bottom of the lower receptacle, whereby said leg functions to restrain the opening of the case, also as movable closure means for one end of the lower receptacle, and said stop engaging with said leg.

3. A pocket case comprising upper and lower members, the upper member being longitudinally movable relatively to the lower member, the bottom of the upper member forming a partition dividing the case into separate compartments, the partition and bottom of the lower member converging so that the upper and lower compartments have greater depth at opposite ends, respectively, and whereby the longitudinal movement of the upper member opens the receptacle at that end of the lower compartment having the greater depth.

4. A pocket case comprising upper and lower members, the upper member being longitudinally movable relatively to the lower

member, the bottom of the upper member forming a partition dividing the case into separate compartments, the partition and bottom of the lower member converging so that the upper and lower compartments have greater depth at opposite ends, respectively, and whereby the longitudinal movement of the upper member opens the receptacle at that end of the lower compartment having the greater depth, means for imposing a yielding resistance upon the longitudinal movement of the upper member.

5. A pocket case comprising upper and lower members, the upper member being longitudinally movable relatively to the lower member, the bottom of the upper member forming a partition dividing the case into separate compartments, the partition and bottom of the lower member converging so that the upper and lower compartments have greater depth at opposite ends, respectively, and whereby the longitudinal movement of the upper member opens the receptacle at that end of the lower compartment having the greater depth, means for imposing a yielding resistance upon the longitudinal movement of the upper member, said means further cooperating with the body of the case to confine the matter deposited therein near the openable end of the case.

6. A pocket case comprising upper and lower members, the upper member being longitudinally movable relatively to the lower member, the bottom of the upper member forming a partition dividing the case into separate compartments, the partition and bottom of the lower member converging so that the upper and lower compartments have greater depth at opposite ends, respectively, and whereby the longitudinal movement of the upper member opens the receptacle at that end of the lower compartment having the greater depth, the upper member provided with a hinged cover.

7. A pocket case comprising upper and lower members, the upper member being longitudinally movable relatively to the lower member, the bottom of the upper member forming a partition dividing the case into separate compartments, the partition and bottom of the lower member converging so that the upper and lower compartments have greater depth at opposite ends, respectively, and whereby the longitudinal movement of the upper member opens the receptacle at that end of the lower compartment having the greater depth, the upper member provided with an article securing keeper.

8. A pocket case comprising upper and lower members, the upper member being longitudinally movable relatively to the lower member, the bottom of the upper member forming a partition dividing the case into separate compartments, the partition and bottom of the lower member converging so

that the upper and lower compartments have greater depth at opposite ends, respectively, and whereby the longitudinal movement of the upper member opens the receptacle at 5 that end of the lower compartment having the greater depth, the upper member provided with an article securing keeper including a pin preventing the insertion therein of an article not provided with a recess register- 10 ing with said pin.

9. A pocket case comprising upper and lower members, the upper member being longitudinally movable relatively to the lower member, the bottom of the upper member 15 forming a partition dividing the case into separate compartments, the partition and bottom of the lower member converging so that the upper and lower compartments have greater depth at opposite ends, respectively, 20 and whereby the longitudinal movement of the upper member opens the receptacle at that end of the lower compartment having the greater depth, means for imposing a yielding resistance upon the longitudinal 25 movement of the upper member, said means cooperating with the body of the case to confine the matter deposited therein near the openable end of the case, the wall at the openable end of the case being hinged.

30 10. A pocket case comprising upper and lower members, the upper member being longitudinally movable relatively to the lower member, the bottom of the upper member forming a partition dividing the case into 35 separate compartments, the partition and bottom of the lower member converging so that the upper and lower compartments have greater depth at opposite ends, respectively, 40 and whereby the longitudinal movement of the upper member opens the receptacle at that end of the lower compartment having the greater depth, means for imposing a yielding resistance upon the longitudinal movement of the upper member, said means co- 45 operating with the body of the case to confine the matter deposited therein near the openable end of the case, the wall at the openable end of the case being hinged, the upper member provided with a hinged cover 50 and the latter provided with an exterior article holding longitudinal groove.

11. A pocket case comprising upper and lower members, the upper member being longitudinally movable relatively to the lower member, the bottom of the upper member 55 forming a partition dividing the case into separate compartments, the partition and bottom of the lower member converging so that the upper and lower compartments have 60 greater depth at opposite ends, respectively, and whereby the longitudinal movement of the upper member opens the receptacle at that end of the lower compartment having the greater depth, means for imposing a 65 yielding resistance upon the longitudinal

movement of the upper member, said means cooperating with the body of the case to confine the matter deposited therein near the openable end of the case, the upper member provided with an article securing keeper including a pin preventing the insertion therein of an article not provided with a recess registering with said pin, the upper member provided with finger notches in the sides at their upper edges. 75
